CLAIM

The ornamental design for a pressure washer, therefor as shown and described.

DESCRIPTION

FIG. 1 is a front right perspective view of the pressure washer according to a first embodiment of the invention. FIG. 2 is a front left perspective view of the pressure washer according to a first embodiment of the invention. FIG. 3 is a rear left perspective view of the pressure washer according to a first embodiment of the invention. FIG. 4 is a rear right perspective view of the pressure washer according to a first embodiment of the invention. FIG. 5 is a front view of the pressure washer according to a first embodiment of the invention. FIG. 6 is a rear side view of the pressure washer according to a first embodiment of the invention. FIG. 7 is a left side view of the pressure washer according to a first embodiment of the invention. FIG. 8 is a right side view of the pressure washer according to a first embodiment of the invention. FIG. 9 is a top view of the pressure washer according to a first embodiment of the invention; and, FIG. 10 is a bottom view of the pressure washer according to a first embodiment of the invention. Any elements shown in broken lines in the Figures form no part of the claimed invention, and are instead included to show environmental aspects of the claimed invention.
